MEANS FOR IMPARTING SURFACE FINISH TO PAPER.

1,278,659.

Specification of Letters Patent. Patented Sept. 10, 1918.

Application filed February 2, 1918. Serial No. 215,175.

To all whom it may concern:

Be it known that I, HENRY P. HOWE, a citizen of the United States, residing at Steep Falls, in the county of Cumberland 5 and State of Maine, have invented new and useful Improvements in Means for Imparting Surface Finish to Paper, of which the following is a specification.

This invention has relation to machines for imparting a surface finish to paper sheets and more particularly to those machines which impart to such sheets what is known as a "linen finish". Such machines are frequently termed plating machines, as heretofore it has been customary to obtain the surface or linen finish, by arranging the sheets in a pile, the sheets of paper alternating with sheets of linen, with metal plates forming the top and bottom and interspersed 15 through the pile, and then passing the pile between pressure rollers, the result of the compression being that the minute projections on the surfaces of the linen sheets are forced into both faces of each paper sheet, 20 giving it the appearance of linen. Such a process of linen finishing paper is necessarily slow, as it requires that the sheets of linen and of paper and the metal plates shall be separately handled and placed in a pile, and 25 then separated after being subjected to the pressure rolls; and moreover a number of operators are needed for each machine, some 30 to form the piles, some to separate them, and at least one other operative to lift the heavy 35 pile and oversee its passage between the pressure rolls.

The particular object of the present invention is to eliminate the necessity of forming the sheets in piles, the muscular effort required to move the heavy piles from the pile-forming table to the plating machine having the pressure rolls, and the necessity of having a large number of linen sheets, which are easily creased on account of their 40 flimsy character and are difficult to handle, and also to reduce the number of operatives necessary to effect the surface-finishing of the paper sheets.

I accomplish these objects by the provision 45 of a machine which is automatic in operation and in which the sheets are plated or linen-finished one at a time.

The machine comprises two coating members which are surfaced to impart the linen

or surface finish to the paper sheets, and 55 which are caused to move or oscillate first in one direction and then in the other, so that on one stroke one sheet of paper may be passed between the members and delivered to one side of the machine, and upon the next 60 stroke a second sheet of paper may be finished and delivered to the other side of the machine. During their movement, these members are so forced together that their operative faces are impressed into both sides 65 of the sheet which is located between them, thereby imparting the desired finish to such sheets. Preferably the operative face of each member is formed of a sheet of linen or other fabric, and the member itself consists 70 of a metallic plate which is flexible, and to which said sheet is secured.

The invention is capable of many embodiments, and in the form shown it consists of two oscillatory plates or members which are 75 fed first in one direction and then in the other direction by pressure rolls between which said members are arranged. The pressure rolls not only serve the purpose of feeding the members, but they impart the 80 pressure thereto necessary for the embedding of the fabric sheets in the sides of the paper sheets. In connection with the plating members, I preferably employ, on both sides of the machine, means for separating 85 the ends of the members, means for feeding sheets of paper thereto in alternation, and means for insuring the stripping of the paper sheets from the members and the delivery of such sheets at the completion of the 90 stroke of the members.

Referring to the drawings, which illustrate the best embodiment of the invention now known to me,

Figure 1 represents a side elevation of 95 the machine.

Fig. 2 represents a front elevation thereof with the paper feeding and control mechanism omitted.

Fig. 3 illustrates in side elevation a portion of one of the operating members.

Fig. 4 illustrates pneumatic mechanism for stripping the paper sheet from the members.

It will be understood, of course, that the machine is illustrated more or less conventionally for the purpose of making clear the principle upon which it operates, that the proportions of the parts as shown may be 105

greatly varied, and that their arrangement will be such as to effect the purposes desired.

Any suitable frame-work may be employed, but, for purposes of illustration, I have shown the machine as being provided with two end frames or standards 10, 10, connected by a cross brace 11. Journaled in suitable bearings in these standards, are two powerful compression rolls 12, 13, of which one is adjustable in relation to the other. As illustrated, the shaft 18 of the roll 13 is mounted in vertically adjustable boxes 14 which are capable of being moved up and down independently of each other by screw bars 15 having handles 16 by which they may be rotated. These screw bars are in threaded engagement with stationary nuts 17 secured at the upper ends of the standards. The peripheral portions of the compression rolls may be slightly roughened if desired. To insure synchronous oscillation, the shaft 18 of the roll 13 and the shaft 19 of roll 12 are provided with intermeshing gears 20, 21, having a ratio of 1 to 1. Oscillatory movement is imparted to the rolls by any suitable means, as, for example, from the main driving shaft 22 which has a pulley 23 by which it may be continuously rotated in one direction. The said shaft is provided with a crank 24, the crank pin 25 of which is adjusted toward and from the axis of the shaft 22 by a screw bar 26 in threaded engagement with a block 27 carrying said pin. The crank pin is located in a slot 28 formed in a lever or arm 29 projecting from a gear segment 30 which is pivoted upon a stud 31. The segment is in toothed engagement with a pinion 32 on the shaft 19. As a result of this construction, the oscillation of the segment causes an oscillation of the two rolls 12 and 13. The stroke of the segment may be varied by adjusting the crank pin 25. In lieu of these parts, any other suitable mechanism may be employed for effecting the oscillation of the rolls.

The plating elements, as illustrated, consist of two plates or members 40, 40, each formed of a metal plate or sheet which may be curved in the direction of its length. To each end of these plates or members is secured a head 41 which supports a roll 42 capable of longitudinal adjustment in relation to the plate or member. Covering the operative face of each member, there is a sheet 43 of linen or equivalent material for imparting the desired surface-finish to the paper sheet. Each of these sheets 43 is passed over the rolls 42 of the member carried thereby, and the ends of the sheet are secured to the heads 41 by clamps 44. To maintain the proper tension on the sheets 43, the rolls 42 of each member are forced yieldingly in opposite directions by springs 45 which bear against the blocks 46 in which

the rolls 42 are journaled. The said blocks are mounted to slide in guideways afforded by the head. As a matter of incidental construction, the tension on the springs may be varied by abutment screws 47 which may be locked after adjustment by lock nuts 48. The ends of the screws are shown as engaging the heads of pins 49 extending into the ends of the springs 45.

The two plating members 40, 40, are located between the rolls 12 and 13 and are pressed firmly and tangentially against each other, and, as the said rolls are oscillated first in one direction and then in the other, the plates or members 40 are likewise moved or fed between the rolls first toward one side of the machine and then toward the other. To permit the introduction of sheets of paper between these members and the discharge of sheets therefrom, the ends of these members are separated. For this purpose they are preferably curved and are caused to travel in curvilinear paths. Consequently the machine is shown as provided on each of its two sides with a pair of brackets 50, 50. Said brackets are secured to the standards 10 and are provided with curvilinear guideways 51, 51, into which project rollers 52 carried by the heads 41 of the members 40. If desired, these rolls may be mounted upon studs extending laterally from the ends of the heads, or they may, if desired, be located upon the shafts 53 on which the rolls 42 are journaled as indicated in Fig. 3.

By reason of the construction thus described, it is apparent that, when the two members are passed between the rolls first in one direction and then in the other, the forwardly moving ends of the members are separated so that the sheet of paper being fed between them is discharged, and a new sheet of paper may be inserted to be carried by them in the opposite direction during the next stroke.

For introducing sheets of paper between the plating members, any suitable feeding mechanism may be provided. For this purpose, I have shown conventionally two conveyer belts 54, 54, which are arranged on opposite sides of the machine and which are mounted upon pulleys 55, 56. Power may be imparted to one of the pulleys of each belt or conveyer so as to cause the belt to be moved in the direction of the arrow at the desired speed. These conveyers or belts are so located as to feed sheets of paper in alternation to the plating members. I have also shown conventionally means for causing the sheets to be fed singly; that is, I have illustrated in connection with each belt stop or abutment means 57 carried by levers 58 pivoted at 59 and arranged to be moved by a cam 60 mounted upon the end of the roll 12. These parts are shown more or less conven-

tionally, but it will be understood that the stop or abutment 57 is normally in an active position to prevent the feeding of a sheet, as shown on the right-hand side of the machine in Fig. 1, but may be lifted by the cam 60 to permit the passage of a single sheet thereunder as shown at the left-hand side of the same figure.

I provide for insuring the stripping of the finished sheet from the plating members, and its delivery to a suitable table or receptacle. Any suitable mechanism for this purpose may be employed, but I preferably use a blast of air to lift the advancing edge of the paper sheet from the lower member as illustrated in Fig. 4. This stripping mechanism comprises a plurality of nozzles 60 having flat narrow mouths arranged in fairly close proximity to the path of movement of the lower of the two plating members. There are two sets of these nozzles, one on each side of the machine, and they are arranged to direct their blasts or streams of air inwardly toward the middle portion of the machine. Each set of nozzles is supplied with air from a pipe 61 on which the nozzles are mounted and which communicates with the interior of the nozzles through suitable ports or openings 62 as indicated in Fig. 4. Any suitable conduits for conducting air to the pipes 61 may be employed. As shown, I have illustrated at 63 a fan delivering air under pressure to a conduit 64, from which pipes 65 lead to pipes 62. The top of each nozzle is formed or provided with a flat plate 67, and these plates form guides over which the sheets of paper may pass to receptacles indicated conventionally at 68.

The operation of the machine will be readily understood from the foregoing description. There are two operatives necessary for the most efficient operation of the machine, one standing at each side of the machine in proximity to the conveyer belt 54 thereat. Each operator places a sheet of paper to be finished, which is in proper temper, upon the adjacent feeding conveyer, and, when the plating elements have nearly completed their movement toward that side of the machine, the stop 57 is lifted to permit the conveyer to feed the sheet between the separated ends of the plating elements. Thereupon the direction of rotation of the rolls, 12, 13, is reversed, and the two plating members are then moved in the opposite direction, carrying the sheet of paper with them between the rolls, with the result that the sheet is progressively subjected to great pressure between the rolls and the plating elements, and the fabric sheets carried by the plating elements are impressed or embedded more or less in both sides of the sheet. As the paper emerges between the rolls and the then advancing ends of the plating elements are separated, blasts of air from the nozzles 60

are directed against the front edge of the sheet of paper to lift it from the lower member 40, and cause it to pass over the guides 67 and be delivered to the receptacle 68 on the opposite side of the machine from which the sheet of paper was started. Sufficient inertia or momentum is imparted to the sheet by the movement of the plating members, that, when it is released thereby, it slides over the guides 67 and comes to a state of rest in the receptacle 68. The operator, on the other side of the machine, having in the meantime placed a sheet of paper upon the other conveyer 54, it is apparent that, upon the reverse movement of the stroke of the plating members, a second sheet of paper will be carried by them between the rolls and delivered to the other receptacle 68. Thus, with each stroke of the plating elements, a sheet of paper is carried by them between the pressure rolls and is finished on both sides thereof, the stop mechanism insuring that the sheets of paper shall be properly fed in alternation from opposite sides of the machine. Of course in slack times, the machine may be attended by but one operator who feeds the sheets of paper from only one side of the machine, but, to secure the maximum efficiency, two operators are employed to insure the finishing or plating of one sheet for each strip during each stroke of the plating members. The feeding movement of the plating members may be varied by varying the arc of movement of the segmental gear 30, according to the size of the sheet of paper to be finished.

It is evident that the machine may be made in different sizes and that the length of each plating member may be such that the rolls will make one or more complete rotations during each stroke of the plating members. In such case, of course, the brackets, having the guideways for the plating members, will be of proper length.

When the linen facings of the plating members become worn, they may be easily renewed by removing the clamping plates 44, in which case it may be necessary to vertically adjust the roll 13 so as to permit the separation of the plating members.

The plates, which form the members, are relatively thin and more or less flexible, and their outer surfaces may be roughened to insure a non-slipping contact between said members and their respective coöperating and feeding pressure rolls.

As indicated in the foregoing part of the specification, it is quite apparent that many changes may be made in the precise mechanism which I have illustrated and described without departing from the spirit and scope of the invention as set forth in the claims.

Having thus explained the nature of my said invention and described a way of making and using the same, although without at-

tempting to set forth all of the forms in which it may be made or all of the modes of its use, what I claim is:—

1. A paper-finishing machine comprising
5 the combination of a pair of oscillatory curved paper-finishing plates for simultaneously surface-finishing both sides of a sheet of paper, means for pressing them tangentially one toward the other, and mechanism for effecting the oscillation of said plates, whereby sheets of paper to be surface-finished may be fed alternately in opposite directions between them. 70
2. A paper-finishing machine comprising
15 the combination of a frame, a pair of oscillatory curved paper-finishing plates supported by said frame and having their faces covered with confronting layers of fabric or their equivalent for simultaneously imparting a rough finish to both sides of a sheet of paper, means supported by said frame for pressing said members one toward the other to press a sheet of paper between them, and means for causing the oscillation of said members, whereby sheets of paper may be fed alternately in opposite directions between them. 80
3. A paper-finishing machine comprising the combination of a pair of oscillatory curved paper-finishing members having con-
30 fronting layers of fabric or their equivalent for simultaneously imparting a rough finish to both sides of a sheet of paper, means for pressing said members one toward the other to press a sheet of paper between them, means for causing the oscillation of said members, and means on both sides of said members for feeding sheets alternately to said members, whereby during each stroke of said members a sheet is carried between
35 and surface-finished by them. 90
4. A machine for surface-finishing paper comprising coöperating plating members, each member consisting of a plate, a fabric covering the operative face of the plate, and means for oscillating the members against each other and under pressure and separating their advancing ends, whereby a paper sheet may be surface-finished on both faces between the members when so oscillated and delivered at the end of the stroke thereof. 95
5. A machine for surface-finishing paper comprising coöperating plating members, each member consisting of a plate, a fabric covering on the operative face of each plate, means for oscillating the members against each other under pressure, whereby a paper sheet may be surface-finished between the elements when so oscillated, and paper-feed-
55 ing means on opposite sides of the machine for feeding sheets of paper to said members. 100
6. A machine for surface-finishing paper comprising oscillating plating members both surfaced with material to be impressed in the paper, means for oscillating the members under pressure, means for feeding paper
65 110
7. A machine for surface-finishing paper comprising oscillating plates continuously supported by the frame-work thereof, each plate having a fabric facing on its operative face, automatic means for oscillating the plates against each other under pressure, and means for maintaining the fabric facing on each plate under tension thereon. 120
8. A machine for surface-finishing paper comprising coacting plates continuously sup-
80 ported by the frame-work thereof, each plate curved in the direction of its length and having a fabric facing, opposing rolls for pressing said plates against each other in rolling contact, and automatic means for effecting the oscillation of said rolls and plates. 125
9. A machine for surface-finishing paper comprising coöperating oscillatory plates, each curved in the direction of its length, each plate having means thereon for imparting a fabric imprint, opposing rolls for oscillating the plates against each other under pressure, and means for guiding said plates. 130
10. A machine for surface-finishing paper comprising flexible metallic plating members, attached to and constituting an operative element of such machine, a fabric covering the operative face of each member, and means for moving said members in rolling contact against each other under pressure first in one direction and then in the other, whereby during each stroke thereof a sheet of paper may be surface-finished. 140
11. A machine for surface-finishing paper comprising oscillatory plating members ar-
105 ranged to be oscillated in rolling contact, and guideways on the opposite sides of the machine for supporting one of the members, and arranged to separate said member from contact with the other member when said members are shifted from plating to non-plating position. 150
12. A machine for surface-finishing paper comprising oscillatory plating elements, means for oscillating the plating elements, and means for guiding the elements as they are shifted from plating contacting relation to non-plating position and arranged to separate the elements from contacting en-
115 gagement when so shifted. 160
13. A machine for surface-finishing paper comprising oscillatory plates, each having a fabric covering for giving a linen finish to paper on both sides thereof, means arranged to feed paper thereto from opposite sides of the machine, and means on both sides of the machine for receiving the paper sheet from the finishing means. 170
14. A machine for surface-finishing paper 180

- comprising oscillatory plating members for surface-finishing both sides of a sheet of paper, a conveyer on each side of the machine arranged to feed paper sheets to said 5 plating means, a stop associated with each conveyer for arresting the movement of the sheet toward the plating means, and means for alternately lifting said stops from arresting position to permit the feeding of the 10 paper when the plating means are in position to receive the paper.
15. A machine for surface-finishing paper comprising oscillatory plating members for surface-finishing both sides of a sheet of 15 paper, guides for guiding the discharge of the finished paper, an air nozzle for projecting a blast of air under the paper sheet as it approaches the nozzle so as to lift it from the plating member which supports it, and 20 means for supplying air under pressure to said air nozzle.
16. A machine for surface-finishing paper comprising pressure rolls, fabric-surfaced plating members arranged between said rolls 25 adapted to surface-finish a sheet of paper placed between them, one of said members being curved in the direction of its length, and mechanism for automatically oscillating said rolls and thereby moving said members alternately in opposite directions.
- 30 17. A machine for surface-finishing paper comprising pressure rolls, mechanism for oscillating said rolls, coacting plates between said rolls and adapted to surface-finish a sheet of paper placed between them, and mechanism for guiding and separating said plates as they are moved back and forth by said rolls.
- 35 18. A machine for surface-finishing paper comprising a frame, and the following instrumentalities supported by said frame, to wit: pressure rolls, mechanism for oscillating said rolls, and plating members
- movable back and forth between said rolls under pressure, each member consisting of a 45 plate, a sheet of fabric covering the operative face thereof, and means for holding such fabric sheet taut on the face of the plate.
19. A surface-finishing machine comprising plating members having confronting 50 fabric-surfaced faces, means for guiding said members in tangential paths, pressure rolls pressing said members together in tangential contact, and means for automatically oscillating said rolls.
- 55 20. A machine for surface-finishing paper comprising coacting plates, a sheet of fabric covering the operative face of each plate, and mechanism for automatically moving said plates backward and forward in rolling contact, whereby during each stroke of said plates a sheet of paper fed between said plates may be compressed progressively from end to end and finished on both faces simultaneously and then delivered automatically from said plates at the completion of such stroke.
- 60 21. A machine for surface-finishing paper comprising coacting plates movable longitudinally in tangential paths and each 65 curved in the direction of its length, and instrumentalities for oscillating, guiding and pressing them together in rolling contact.
- 70 22. A machine for surface-finishing paper comprising coacting plates movable longitudinally in tangential paths and each 75 curved in the direction of its length, pressure rolls on opposite sides of said plates for pressing said plates against each other in rolling contact, and means for automatically oscillating said rolls and thereby oscillating said plates.

In testimony whereof I have affixed my signature.

HENRY P. HOWE.
